UNITED STATES PATENT OFFICE.

PRESTON E. GILLING, OF EAST ORANGE, NEW JERSEY, ASSIGNOR TO WIRELESS SPECIALTY APPARATUS COMPANY, OF BOSTON, MASSACHUSETTS, A CORPORATION OF NEW YORK.

ELECTRICAL CONDENSER.

Application filed March 19, 1925. Serial No. 16,597.

This invention relates to electrical condensers of the stack type, and particularly to condensers of small capacity adapted for low potential service. This type of condenser usually consists of a stack of sheets which usually have small superficial area and are so small in number that the stack is so thin as to be more or less flexible. The sheets consist usually of metal foils (armatures) and mica sheets (dielectrics), the diameter of the mica sheets being greater than the foil sheets so as to provide insulating margins at the sides of the stack save at the sides out of which project foils of opposite polarities at spaced-apart portions of the sides.

The object of the invention is an improved means for holding the sheets in the form of a stack, said means preferably having additional functions to be described.

The invention consists of the features illustrated in the drawings, described hereinafter and pointed out in the claims.

In the past the problems involved in this type of condenser have included those relating to the encasing or protection of the electrical stack itself comprising the armature sheets and dielectric sheets, the maintenance of a given desired capacity of such stack and the matter of cost involved in a practical solution of said features. In the present invention these objects are obtained in a practical manner and at low cost.

Of the drawings—

Fig. 1 is a plan of a punched sheet metal blank which is to be bent around the condenser stack.

Fig. 2 is a plan showing the condenser stack in dotted lines, with insulating strips on its faces, and with the punching or stamping of Fig. 1 partially applied at one end of the stack, by bending along the dot and dash lines A, A of Fig. 1.

Fig. 3 is a plan like Fig. 2 but with the stamping at the right-hand end fully applied to the stack, by bending along the dot and dash lines B, of Fig. 1.

Fig. 4 is a plan like Figs. 2 and 3 but with two duplicate stampings C of Fig. 1 fully applied to both the right and left-hand ends of the condenser stack.

Fig. 5 is a section at 5—5 of Fig. 4.

Fig. 6 is a section at 6—6 of Fig. 5.

The invention is particularly applicable

to small and low capacity condensers, although it is capable of application to electrical condensers of other types. In prior condensers of such small type wherein metal clips were employed to retain the condenser sheets in stack form, and also among other things to compact or clamp the stack sheets together, either the clips have been more or less subject to disassociation from or movement relative to the stack, or else for the purpose of preventing such removal or relative movement, means have been provided which entered into or extended through the stack or insulating strips at the faces thereof, for the purpose of holding the metal clips or clamps in permanent engagement with the stack. Such means for securing together the stack and its securing means, have been objectionable for various reasons among which were increased costs for labor and materials.

The particular object of the present invention is an improved means for permanently holding together the stack and the metal securing means or clamps.

According to my invention the stack and the securing means therefor are held together without the necessity of any part extending through the stack or even entering into any part thereof or of the insulating strips at the stack faces.

In Fig. 1 is shown a sheet metal blank which has been stamped to the shape shown by means of any suitable dies in a punching press. The metal may be brass, steel, copper, or any other suitable metal.

In Fig. 2 is shown in dotted lines a condenser stack having capacity determined by the number of mica sheets M and foil sheets F¹ and F² of opposite polarity. The foils F¹ of one polarity project from the left end of the stack and (when more than one foil is used) several of such foils FF¹ are folded over on a face of the stack as shown at the left in Fig. 2. Similarly the foils F² of opposite polarity project from the right-hand end of the stack and are folded over at FF² on a face of the stack. On the two flat faces of the stack are insulating strips I¹, I² (see Figs. 5 and 6) which preferably extend beyond the mica sheets M which in turn extend (at the stack-sides from which the foils do not project) beyond the foil sheets, F¹, F². The foils F¹ and F² at the respective ends

of the stack are folded over on top of one or the other of said insulating strips I^1 , I^2 .

Insulating strips I^1 , I^2 , preferably consist of single strips of any suitable insulating material, but each or either of them may consist of several sheets of mica like the individual mica sheets M stacked alternately with the foil sheets F^1 , F^2 .

As shown in Figs. 2-4, insulating sheets I^1 , I^2 are cut to a shape wherein their opposite sides at one end of the stack (as at the left, Fig. 2) converge from the end of the stack as indicated at G . Likewise, at the right-hand end of the stack, at G (when the completed condenser is to have two metal members C as in Figs. 4-6).

In Fig. 2 a metal stamping or punching like that shown in Fig. 1 has been bent along the two lines A , A of Fig. 1, so as to produce a U-form; and this has been applied to the right-hand end of the stack of Fig. 2, so that one of the interior walls of the U-shaped device makes contact with the folded foils FF^2 thereby constituting the metal U-clip a terminal of the condenser. Thus, in Fig. 2, the metal clip has been partially combined with the condenser stack.

In Fig. 3 the metal clip C has been fully secured to the condenser stack, by the bending around the sides of the stack of the four parts E shown in Fig. 1, the bending having taken place along the four lines B of Fig. 1. As shown in Fig. 1 the lines B are at an angle to the main body of the punching and generally at right angles to lines A , A . This angle to the main body corresponds with the angular or converging sides G of insulating strips I^1 , I^2 of Figs. 2-4. Thus, when in Fig. 3 the bending along lines BB of Fig. 1 has been effected, the four parts E of Fig. 1 overlie the converging sides of the stack, i. e. of insulating strips I^1 , I^2 which complete the stack and insulate the stack as a whole from the stack terminals. That is, the lines of bends B of Fig. 1 are parallel with the converging sides G of the stack when the metal clip C of Fig. 1 is completely combined with the stack as is shown in Fig. 3.

In Fig. 4 is shown the completed condenser, wherein a duplicate metal clip C has been completely applied to the left-hand end of the stack, the blank for such left-hand clip being a duplicate of the blank shown in Fig. 1.

The bending of the blank of Fig. 1 along the dot and dash lines A and B may be effected manually but preferably is done by means of a suitable power press. By means of such press also, when the clip C is put in place on the stack, the entire clip may be and preferably is deformed so that it clamps the entire stack between its legs and compresses the clip into good electrical contact with the folded foils. Such clamping action holds the

entire stack under sufficiently high mechanical compression, especially the armatures F and the dielectrics M , to maintain substantially unchanging capacity of the stack. The initial bending of metal clip C into U-form 70 may be effected prior to placing it around the end of stack S . After the deformation of the clip as a whole, and while the dies of the press are in their positions corresponding with the deformed conditions of the clip, 75 the portions E may be bent around the sides of the stack by another operating portion of the press.

The bending operations, however, may be 80 as follows:

First, before there is any combination of the metal clip with stack S , the blank of Fig. 1 is put in a press and the parts E are bent over at right angles along the lines B . Then the resulting blank, in another operation, in another press, is bent to U-form 85 along the lines A , A . Then the resulting blank is applied around the end of stack S and the combination is placed in a press and the entire clip deformed into compressing 90 relation with the stack. When the condenser has two clips as shown, both are applied and then both simultaneously deformed.

The deformed U-clip or clips alone, irrespective of parts E , serve as the securing means for holding the micas M and foils F , F^2 in stack form; but without some means of holding such securing means to the stack, the securing means is liable to become disassociated from the stack; and it is the parts E with the angular or side-converging stack construction described, which permanently combine the clips with the stack. 100

In Fig. 5 are shown the foils FF^1 projecting from the left of the stack S and folded over on top of insulated strip I^1 ; the left-hand clip C being then applied. Likewise at the right, the foils FF^2 of polarity opposite the foils FF^1 and projecting from the right-hand end of stack S are folded over on the outer face of the insulating strip and then the duplicate U-clamp applied. 110

In Fig. 6, which is a view at right angles to that of Fig. 5, the completed condenser is shown, with the clip parts E bent around the sides of the stack. 115

It will be seen from the above that the clips C and the stack are permanently held together by means of the construction comprising the converging sides G of the stack (Figs. 2 and 3) and the bends B of the blank of Fig. 1 paralleling said converging sides. That is, the metal clips and the stack are held together in such wise as to prevent lateral movement of the clips either disassociating them from the stack or permitting any relative movement between the clips and the stack. 120

As illustrated in Figs. 4-6, the stack S is 125

substantially enclosed by the construction including the insulating strips I^1 , I^2 and the metal clips C including their bent-over portions E of Fig. 6, so that substantially a box-shaped structure is formed about the stack S.

- Thus the construction of the metal clips (which constitute the means for securing the condenser sheets together in the form of a stack) co-operates with the converging-side 10 construction of the stack to hold such securing means permanently in immovable relation with the stack, and this without any parts (either integral with the clips or separate therefrom but combined therewith) 15 which either extend through the stack or enter into insulating strips I^1 or I^2 . The co-ordinating angular constructions of the metal clip and the stack sides constitute this means for holding the clip and the stack 20 permanently in co-operative relationship.

In the example shown the clips C, by deformation into compressing relation with the stack, act as stack clamps; and the metal clips, by means of the folding over of the 25 foils and the good electrical contact between the clips and the foils, constitute circuit terminals for the condenser, and this disclosure constitutes a preferred embodiment of the invention. But I contemplate that the invention 30 may be employed in other forms whether or not the clips serve both as clamps and circuit terminals or either of them; and the construction of the invention involving the converging stack sides and corresponding 35 bends of the metal clips may be employed whether or not the clips act as stack clamps or as terminals. Preferably however in all cases the clips in the invention (when in U-form) preferably are deformed on the 40 stack so as to act as clamps compressing the stack-sheets into substantially intimate contact with one another and thereby maintaining a substantially constant condenser capacity. When the construction involves 45 two clips, the combination permits them to extend very close together as shown, so that when the clips act as clamps, substantially the entire active area of the stack-sheets is held under compression.

50 The clips C and insulating strips I^1 , I^2 hold stack S, otherwise flexible, in rigid condition.

I particularly point out and distinctly claim the part, improvement or combination which I claim as my invention or discovery, as follows:

1. In an electrical condenser of the stack type having a sheet metal stack-securing means, the means for holding the stack and 55 securing means together which comprises a stack-construction including a stack of condenser sheets, and insulating strips on the two stack-faces, each of the opposite sides of each insulating strip having edges converging inwardly toward one another from 60 its ends; and a construction of the stack-securing means which involves duplicate metal U-clamps at the opposite stack ends, each U-clamp having four bends generally at right angles to the U-bend and paralleling 70 said converging sides of the insulating strips; said duplicate U-clamps being deformed into compressing relation with the insulating strips and stack, and four portions of metal bent over at said four bends 75 and overlying the converging sides of said insulating strips; and said U-clamps, their said bent-over portions and said insulating strips substantially enclosing the stack of condenser sheets.

2. In an electrical condenser of the stack type having a metal stack-securing means, the means for holding the stack and the securing means together which comprises a stack construction wherein the opposite 80 sides of the stack each has edges converging inwardly toward one another from the stack ends and wherein foils of opposite polarity projecting from opposite ends of the stack are folded over upon a stack face; and a 85 construction of the sheet metal stack-securing means involving duplicate parts at the two stack ends, each having a U-bend and four bends generally at right angles to the U-bend and paralleling said converging 90 stack-ends, said U-bends extending over the stack ends; said duplicate portions being deformed into compressing relation with said folded foils of opposite polarity respectively, thereby compacting the stack and constituting the U-clamps as stack terminals; and four portions of metal bent over at said 95 four bends and overlying said converging stack sides; and said U-bend and bent-over metal side portions substantially enclosing the ends and sides of the stack, whereby said duplicate members substantially enclose the entire stack.

3. In an electrical condenser of the stack type having a sheet metal stack-securing means, the means for holding the stack and the securing means together, which comprises a stack construction wherein the opposite sides of the stack each has edges converging inwardly toward one another from its ends; and a construction of the sheet metal stack securing device which involves 100 duplicate parts at the two stack ends, each having a U-bend and also four bends generally at right angles to the U-bend and paralleling said converging stack sides; said U-bend extending over and substantially enclosing the stack ends; and portions of metal bent over at said four bends and extending 105 in pairs over opposite converging stack sides and substantially enclosing the latter, whereby said two U-members and their bent-over portions substantially enclose the entire stack.

4. In an electrical condenser of the stack 110

- type having a sheet metal stack-securing device, the means for holding the stack and securing device together which comprises a stack construction including a stack of 5 condenser sheets, and insulating strips on the two faces of said stack, said insulating strips having oppositely converging sides; and a construction of sheet metal stack-securing device involving two bends along 10 lines paralleling said converging sides of the insulating strips; and portions of metal bent over at said four bends and overlying the converging sides of said insulating strips, whereby said strips and the stack-securing 15 device co-operate in holding the securing device and stack-sheets together.
5. In an electrical condenser of the stack type having a sheet metal stack-securing device, the means for holding the stack and securing device together which comprises a 20 stack construction having oppositely converging sides, and stack foils of one polarity projecting from an end of the stack and folded over on the face of the stack; and a 25 construction of sheet metal stack-securing device involving two bends lying along lines paralleling said converging stack sides; said metal stack-securing device being deformed into compressing relation into said folded 30 foils and the stack itself, thereby compacting the stack and constituting the securing means a stack terminal; and portions of metal bent over at said two bends and overlying said converging stack sides.
- 35 6. In an electrical condenser of the stack type having a sheet metal stack-securing device, the means for holding the stack and securing device together which comprises a stack construction having oppositely converging sides, and stack foils of one polarity projecting from the stack end and folded over upon a stack face; and a construction of sheet metal stack-securing device involving two bends along lines paralleling said 45 converging stack sides, the main body of said securing device contacting with said folded foils; and portions of metal bent over at said two bends and overlying the converging stack sides.
- 50 7. In an electrical condenser of the stack type having a sheet metal stack-securing device, the means for holding the stack and securing device together which comprises a stack construction having oppositely converging sides; and a construction of sheet metal stack-securing device which involves two bends along lines paralleling said 55 converging stack sides; said metal stack-securing device being deformed into compressing relation with the stack, thereby compacting the same; and portions of metal bent over at said two bends and overlying the stack sides.
8. In an electrical condenser of the stack type having a sheet metal stack-securing device, the means for holding the stack and securing device together which comprises a stack construction having opposite converging sides; and a construction of sheet metal stack-securing device which involves two lines of bend into a U-form and four bends 60 generally at right angles to the U-bends but paralleling said converging stack sides; said U-bend enclosing a stack end of greater width between sides; and four portions of metal bent over at said four bends and extending in pairs over opposite stack sides adjacent to said enclosed end, and substantially overlying said stack sides.
9. In an electrical condenser of the stack type having a sheet metal stack-securing device, the means for holding the stack and securing device together which comprises a stack construction having opposite converging sides; and a construction of sheet metal stack-securing device which involves a U- 65 member having four bends generally at right angles to the U-bend and paralleling said converging stack sides; and portions of metal bent over at said four bends and extending in pairs over opposite stack sides and substantially enclosing the same.
10. In an electrical condenser of the stack type having a sheet metal stack-securing device, the means of holding the stack and securing-means together and enclosing the 70 stack sides which comprises a stack construction having opposite converging sides; and a construction of sheet metal stack-securing device which involves bends along lines paralleling said converging stack sides; and metal portions bent over at said bends and substantially enclosing the stack sides.
11. In an electrical condenser of the stack type having a metal stack-securing means, the means for holding the stack and the securing means together which comprises a stack construction having oppositely converging sides; and a construction of sheet metal stack-securing device which involves two bends along lines paralleling said 75 converging stack sides, the bent-over metal portions overlying the stack sides.

PRESTON E. GILLING.
